UNITED STATES PATENT OFFICE.

FRED W. CROCKER, OF NORTH BALTIMORE, OHIO.

ENGRAVER'S SPOON-CLAMP.

No. 909,759.

Specification of Letters Patent.

Patented Jan. 12, 1909.

Application filed October 7, 1908. Serial No. 456,527.

To all whom it may concern:

Be it known that I, FRED W. CROCKER, a citizen of the United States, residing at North Baltimore, in the county of Wood 5 and State of Ohio, have invented certain new and useful Improvements in Engravers' Spoon-Clamps, of which the following is a specification.

This invention relates to engravers' implements, and especially to improvements 10 in clamping-jaws for holding spoons during engraving.

This invention is the result of improvements upon my Patent No. 900,148 issued 15 October 6th, 1908, and is designed to simplify the means for holding and adjusting the clamping-jaws shown in said patent.

The object of the invention is to provide 20 a clamping-jaw of such peculiar construction as to permit a pair of such jaws to be adjusted to fit spoons of various sizes and shapes, and to be operated to hold the spoons in clamped position for the purpose of engraving.

25 A further object of the invention is to provide spoon clamping-jaws adapted to be worked on a plate or key in adjusting the jaws for holding spoons, preparatory to fixing the jaws in clamped position.

30 A still further object of the invention is to provide clamping-jaws having a slot parallel with the base of the jaws and extending inwardly from the face of the jaws and forming a seat or bearing for a suitable 35 plate or key upon which the jaws are operated.

With these objects in view the invention 40 consists of a pair of jaws provided with a serrated edge or rack for the usual pins or stops of an engraver's clamping-block, and having a spoon-seat, and a lateral slot under 45 the seat forming a curved bearing, and a suitable plate fitting the slots for the adjustment of the jaws thereon, and for preventing vertical movement of the jaws in a clamping operation.

In the accompanying drawings forming 50 part of this application: Figure 1 is a top view showing the application of the holder. Fig. 2 is a top view of the jaws and connecting plate or key showing in dotted lines various positions of the jaws on the plate. Fig. 3 is an elevation looking at the inner 55 face of a jaw. Fig. 4 is a cross section taken on the line $x-x$, Fig. 2. Fig. 5 is a trans-

verse sectional view of one of the jaws taken on the line $y-y$, Fig. 3.

The same reference numerals denote the same parts throughout the several views of the drawings.

In this class of work-clamps, and especially such as employ loose jaws or jaws which are not attached or permanently fixed to the clamping-block, it has been found that such jaws are raised, tilted or otherwise 60 disarranged in a clamping operation, and that in clamping the bowl of a spoon it is difficult to keep the jaws properly seated on the clamping block without employing bolts, 65 clamps or similar devices which invariably interfere with the workman. It is therefore the purpose of this invention to overcome such disadvantages and objections, and to furnish simple and inexpensive means 70 convenient of operation whereby the jaws may be made to retain their seat on the clamping-block during clamping operation without employing the usual devices. It is well known that such holders or clamping-jaws should be made in such manner as to assist 75 an engraver in his work and with as little obstruction or interference with work and workman as possible. The construction of the jaws hereinafter particularly described and the means by which they are connected 80 together in a clamping operation will be 85 found to accomplish these ends.

For the purpose of exemplifying the invention, an ordinary engraver's block 1, having a clamping-screw 2, and the usual perforated head 3 provided with stop-pins or pegs 4, is employed.

The spoon seat 5 and lip 6 of the jaws 7 are the same as shown in my aforesaid patent, and the jaws being alike only one of 95 them will be described in detail.

The outer edge of the jaw-base 8 is serrated, notched, racked or provided with teeth 9, which the pins 4 engage preparatory to clamping a spoon between the jaws by 100 operating the clamping-screw 2, to prevent backward movement of the jaws.

A slot 10 extends from the inner face of the jaw under the spoon-seat parallel with the jaw-base and terminates in a semi-elliptical or curved base 11 opposite the teeth 9.

The edge of the spoon-bowl fits under the lips 6, so that in a clamping operation it is necessary to provide means to prevent the jaws raising or tilting up from the block- 110

head, and this means consist of an elliptical plate 12 fitting the slots 10 of each jaw and forming a connection or key between the jaws.

5 It is obvious that the jaws may be moved or slid about, back and forth on the plate 12 to adjust and position them for holding a spoon-bowl, and that the plate counteracts the clamping pressure of the jaws on the 10 spoon and prevents vertical movement of the jaws in a clamping operation.

Having thus described my invention, what I claim as new and desire to secure by Letters Patent is:

15 1. The combination with an engraver's clamping-block having suitable stop-pins, of a pair of clamping-jaws having a seat for a spoon-bowl and a serrated edge engaged by said pins, a slot extending from the inner 20 face of each jaw under said seat, and a plate fitting the slots to prevent vertical movement of the jaws in a clamping operation.

2. The combination with a clamping-block having means for attaching clamping-jaws thereto, and the said jaws each having a slot 25 extending from the inner face thereof, of an elliptical plate fitting the slots for the purpose of keeping the said faces parallel during a clamping operation.

3. A clamping-jaw of the character described having a serrated outer edge, a spoon-bowl seat, a slot extending from the inner face of the jaw under the said seat and terminating in a curved base opposite the serrated edge, combined with a like jaw, and 35 a plate fitting said jaw slots to parallel the clamping faces of the jaws.

In witness whereof I hereunto set my hand in the presence of two witnesses.

FRED W. CROCKER.
